UNITED STATES PATENT OFFICE.

MARCUS B. BEHRMAN, OF NEW YORK, N. Y., ASSIGNOR TO THE LOX SEAL CORPORATION, OF BROOKLYN, NEW YORK, A CORPORATION OF NEW YORK.

PILE-WIRE CUTTER.

Application filed November 12, 1924. Serial No. 749,447.

My invention relates generally to a pile cutting means for the type of looms which weave pile fabrics and more particularly to an association with the pile wires generally employed in such looms, of a cutter for cutting the loops as the pile wires are withdrawn.

In looms which employ pile wires, the warp threads are generally looped over these wires and when it is desired to produce a cut pile fabric, cutters are so associated with the pile wires that upon withdrawal of the wires from the fabric, the cutters will cut through the loops. Due to the rapidity with which these pile wires are thrown in and withdrawn and the number of threads to be cut upon each withdrawal, each cutting edge is subject to a great number of cutting operations in a short time and therefore dulls quickly and such edges must obviously therefore be either frequently resharpened or frequently replaced.

The use of a cutter which is separable from the pile wire for permitting replacement of the blade is attended with a number of problems, among which is that any arrangement for securing the blade in position which on the one hand will serve to hold the blade in association with the pile wire so that it will not shift therein nor will it be accidentally separated therefrom, may on the other hand so secure the blade as to render its removal difficult and time consuming.

One of the important objects of my invention, therefore, is the provision of an arrangement whereby a cutting blade is so associated with the pile wire that while it is fixedly held in position thereon and against accidental movement, its quick and effective removal is permitted.

Looms of the type referred to are already provided with pile wires and it is one of the important objects of my invention to devise the cutter and its manner of association with a pile wire that the cutter can be associated with the conventional form of pile wire without requiring a replacement of the pile wires or any substantial change or reconstruction therein.

My invention further involves the provision whereby a blade of a flexible wafer type made from sheet material may be employed and an arrangement for so supporting the blade that will not require any sub-

stantial flexing of the blade either for purposes of insertion or for removal.

Where I have attempted to employ an arrangement for holding the blade in position which depends wholly upon a gripping engagement to prevent movement in one direction, I have found that in the movement of the pile wires back and forth in the operation of weaving, the effectiveness of the gripping engagement is diminished to a considerable extent by the fact that grease and oil tend to work into the pile wire and coming into contact with the blade and with the means of holding it in position, tend to cause a loosening of the grip and that as a result a blade will frequently work loose from the holder and move freely in one direction.

My invention, therefore, involves the provision of an arrangement for positively holding the blade in position and coordinately involves more particularly, the association with a gripping engagement for holding the blade in position against movement in one direction of an arrangement for positively holding the blade against movement in the holder in such direction should the blade work loose from its gripping engagement.

My invention further involves the provision of a simple, inexpensive and efficient cutting blade and of a novel, simple, readily operable, inexpensive manner of associating the blade with the pile wire so as to permit the blade on the one hand to perform its function at a maximum of effectiveness, and at the same time to permit of its quick removal and replacement.

For the attainment of these objects and such other objects as may hereinafter appear or be pointed out, I have illustrated one embodiment of the invention in the drawings wherein—

Fig. 1 is an elevational view of the pile wire with the blade in position;

Fig. 2 is an enlarged cross-sectional view centrally longitudinally of the holder portion of the pile wire;

Fig. 3 is a section taken on line 3—3 of Fig. 2;

Fig. 4 is a section on line 4—4 of Fig. 2.

Upon viewing Fig. 1 of the drawings, it will be observed that my arrangement shown in this embodiment for associating the blade with the pile of wire comprises a holder

10 which may be made either integral with the pile wire or an attachment thereto and which is in the form of a thin strip of sheet material bent so as to provide a channelled construction which is preferably, though not necessarily U-shaped in cross section, the channel 13 being defined by the walls 11 and 12 upstanding from the bottom 14, the walls of the channel 13 being spaced so as to freely receive therein the blade, to be described more in detail thereafter, and for reasons that will appear or be pointed out shortly, the part of the wall 11 which extends beyond the channel is caused to gradually increase and then decrease in height towards the front or terminal portion 15^a thereof, which apex portion is curved transversely as more clearly shown in Fig. 3 of the drawing, as a result of which there is formed at the outer end of the wall 11, the spoon-shaped end 15.

The opposite wall 12 terminates a substantial distance short of this apex 15^a of the wall 11 and has extending from this upper edge a flange or extension 17 which is bent across the channel 13 so as to form a crosspiece 18, the free end of which is received through an opening 19 in the wall 11 and secured therein in any preferred or desired manner as by brazing or welding.

The blade 20 may be given the shape shown in Fig. 2 in which it is provided with the bottom 21, the cutting edge 22 at an angle thereto, and the projecting guide and locking member 23 which extends from the blade in a direction opposite from that of the cutting edge 22, and which, as shown, merges into the topmost portion of the blade 22 by the inclined wall 25. The upper edge 26 of this extension is preferably inclined oppositely to the inclination of the cutting edge 22 and its position above the bottom 21 of the blade is such that as the blade is moved along the channel 13, with its bottom 21 in contact with the bottom of the holder 10, the guide extension 23 is moved along beneath the crosspiece 18 with the inclined top 26 thereof in engagement with the crosspiece, so that as the movement is continued, a gripping engagement between the blade and the holder 10 will thereby result, which will be of an increasingly effective character as the blade 20 is moved along the holder.

It will be understood that this character of grip engagement will positively hold the blade against movement beyond the predetermined point toward the front end of the holder, that is, toward the apex 15^a, and that prevention of movement in the opposite direction will be dependent upon the character of the gripping engagement between the inclined surface 26 and the crosspiece 18. I have found that, while this character of gripping action is ordinarily sufficient to hold the blade in position against the move-

ment toward the rear of the holder, that due to the rapidity and frequency of the reciprocations of the pile wire as it functions to cut the loops, that not only will the pile wire heat up, but that grease will work into the channel member, and that as a result thereof, there will be a tendency occasionally for the gripping action between the inclined surface 26 and the crosspiece 18 to become less effective, even to the point where the blade 20 will begin to move back and forth in the holder. For the purpose of preventing any movement of the blade, should the gripping engagement become less effective for the reasons set forth, or for any reasons, I have provided an arrangement which I will now describe:

From that part of the spoon-like end 15, which extends beyond the wall 12, I provide a tang 31 shown more clearly in Fig. 3 of the drawing, and which as will be observed, is cut away along three sides and is bent angularly across the path of the channel 13 with the free end of the tang 31 directed generally toward the front end 15^a and the end 35 thereof will form an abutment across the path of the channel and the inner surface 35^a thereof inclines outwardly from the abutment wall 35 toward the inner surface of the wall 11 into which it will merge.

The blade 20 is provided with a coacting part which in the illustrated embodiment is the slot 32 so positioned that as a blade is caused to have its gripping engagement with the crosspiece 18 as already set forth, the rear end 33 of the blade will be forced over and past the tang 31. In this movement either this rear end 33 of the cutting implement or the tang or both, as the case may be, will flex laterally depending upon the relative stiffness of the materials out of which the blade and the holder are made and the tang will then position itself in the cut away portion 32 of the blade 20 and will position its extreme forward part 35 immediately in back of the wall 36 of the part 33 which wall 36 defines in part the slot 32 and thus serves as a positive stop to prevent movement of the blade beyond it toward the rear of the pile wire.

In the illustrated embodiment, I prefer to show the metal of which the holder is made as being of such character with relation to the metal of which the blade is made, that it is the forward part of the blade 33 which flexes in this movement.

As a result of this arrangement, it will be understood, therefore, that as the blade is moved into the channel 13 toward the inner end, a gripping engagement between the inclined wall 26 and the crosspiece 18 will ensue, which will be of an increasingly effective character as the blade is continued in such movement, and at a predetermined

point, due to the positioning and dimensioning of the various parts, the part 33 will slip over the tang 31, which tang will then be positioned in back of the part 33 to prevent a retrograde movement of the blade, that is, a movement to the right, in Fig. 3. In other words, the gripping engagement between the parts 26 and 18 and the character of the top of the blade are such as to limit the movement of the blade to the left, and the association of the tang 31 with the rear wall 36 of the part 33 will prevent and positively stop any movement of the blade in the opposite direction, that is to the right.

It will be observed that with this arrangement, the inclined surface 26 and the slot 32 are formed on a part of the blade that extends to the rear of the cutting edge 22, and that therefore I not only secure the blade to the holder, wholly through the engagement of that part of the blade which carries no cutting edge, but that the engaging means of which the tang 31 is a part, is positioned at a point in the holder which is open laterally through one side thereof, so that the release of the blade can be quickly effected and where it is desired for any reason whatsoever to effect the release of the blade by breaking off the part 33 thereof, this can be done very readily.

It will be further observed that the height or width of the intermediate part of the spoon is much greater than that of the tang 31 and that the tang is positioned a substantial distance below the top of the spoon, so that the inner surface of the spoon 15 will serve to support and guide the blade end 33 over the inclined surface 35.

Having thus described my invention and illustrated its use what I claim as new and desire to secure by Letters Patent is—

1. For use in looms for weaving pile fabrics, a pile wire having on one end a holder provided with a recess, and a cross-bar crossing said recess above the bottom thereof; and a blade seated in said recess with its cutting edge exposed above the same, said blade having a lower edge to engage the bottom of the holder and an upper edge inclined downwardly and outwardly to wedge against said cross-bar, said incline being of such character that when the blade is moved along the recess toward the free extremity of the pile wire, an increasing gripping engagement will result which engagement will hold the blade in position against removal and means operative upon the movement of the blade into gripping engagement to prevent a movement of the blade in the opposite direction, and means comprising a finger struck up from the holder.

2. For use in looms for weaving pile fabrics, a holder adapted to form a part

of a pile wire and having a channel to receive a cutting implement or blade with one edge of the implement seated on the bottom of the channel, and means on said holder for holding the blade against movement in said channel, including a member formed on the holder inwardly of its free end and projecting inwardly into the channel and spaced a substantial distance below the top of the holder, said member presenting an inclined surface which merges into the inner surface of one of the walls forming the channel in the direction of the rear end of the holder, whereby a blade can be moved over said inclined surface to bring a portion of the blade in back of it.

3. For use in looms for weaving pile fabrics, a holder adapted to form part of a pile wire and having a channel to receive a cutting implement or blade with one edge of the implement seated in the channel, and means for holding a blade against movement on said channel, said means including a member punched up from one of the walls of the channel along three sides and having a portion thereof presented in the path of movement of an implement in the channel, said member being directed generally toward the front end of the holder.

4. For use in looms for weaving pile fabrics, a holder adapted to form part of a pile wire and having a channel to receive a cutting implement or blade with one edge of the implement seated on the bottom of the channel, and means on said holder for holding the blade against movement in said channel, including a member punched up from the holder and having a portion projecting inwardly into the path of a cutting implement in the channel and spaced a substantial distance below the top of the holder, said member extending generally toward the front of the holder.

5. For use in looms for weaving pile fabrics, a holder adapted to form part of a pile wire and having a channel to receive a cutting implement or blade with one edge of the implement seated on the bottom of the channel, and means for holding the blade against movement in said channel, said means including a member punched up from one of the walls of the channel along three sides and forced angularly inwardly into the path of the channel and directed generally toward the front end of the holder and terminating a substantial distance therefrom whereby a blade can be moved in the channel over said member.

6. For use with a holder adapted to form part of a pile wire having a channel to receive a cutting implement with one edge of the implement seated on the bottom of the channel and having a plurality of abutments extending into the path of the implement in the channel, a cutting implement, a plurality

of engaging portions therein all positioned beyond and to one side of the cutting edge, one of said engaging portions on the implement being arranged to coact with one of the abutments on the holder to prevent movement in one direction and another of said engaging portions on the cutting implement being arranged to coact with another of said abutments on the holder to prevent movement in the opposite direction.

7. For use in looms for weaving pile fabrics, a holder adapted to form part of a pile wire and having a channel to receive a cutting implement or blade with one edge of the implement seated on the bottom of the channel, a blade seated in said channel, means for preventing movement of the blade relatively to the channel, said means including a finger projecting integrally from the wall of the channel and directed into the channel generally in the direction of the front end of the holder, the finger being relatively more rigid than the blade so that when a blade is moved in the channel over the finger, the blade will yield to permit a portion thereof to be positioned in abutting relation to and in back of the finger.

8. A pile wire for looms having a blade holder located at one end and having one wall extending beyond the other to form a spoon end for the wire, said holder being provided with a groove formed therein and

having a laterally projecting abutment formed thereon, and a knife blade mounted within said groove and having a part of its perimeter adapted to engage said abutment, said spoon presenting an integral retaining tongue adapted to engage with said blade and cooperate with said abutment to hold said blade within said groove when said blade is moved into its predetermined association with said abutment.

9. A pile wire for looms having a blade holder located at one end thereof and having two walls presenting between them a groove, one of said walls having an abutment formed thereon, a knife blade mounted within said groove and having a part of its perimeter engaging said abutment, and a locking member formed integral with one of said walls and adapted to automatically engage with said blade and thereby cooperate with said abutment to hold said blade within said groove, said member and blade being so arranged and constructed that one will automatically be sprung laterally relatively to the other to permit insertion and removal of said blade without flexing the latter.

In testimony whereof, I have signed this 26th day of September, 1924.

MARCUS B. BEHRMAN.
